UNITED STATES PATENT OFFICE.

HERBERT B. NICKELL, OF PORTSMOUTH, OHIO.

SIGNAL DEVICE.

Application filed March 11, 1926. Serial No. 93,992.

This invention relates to a signal device designed primarily for use on railroads for the purpose of supporting a signal flag or lamp above the track.

5 One of the objects of the invention is to provide a device of this character having a standard provided with novel means for gripping a rail so as to hold the standard in proper position.

10 A further object is to provide the standard with means for suspending a signal lamp in a desired position, there being also a signal flag connected to the standard.

15 With the foregoing and other objects in view which will appear as the description proceeds, the invention resides in the combination and arrangement of parts and in the details of construction hereinafter described and claimed, it being understood 20 that changes in the precise embodiment of the invention herein disclosed may be made within the scope of what is claimed without departing from the spirit of the invention.

25 In the accompanying drawings the preferred form of the invention has been shown.

In said drawings,

30 Figure 1 is an elevation of the signal device, a lamp being shown in one position thereon, said lamp being illustrated with broken lines.

Figure 2 is a side elevation of the device.

35 Figure 3 is an elevation showing the clamping jaws moved apart.

40 Referring to the figures by characters of reference 1 designates a standard to the lower end portion of which are pivotally connected angular strips 2 constituting jaws, these jaws being so shaped that, when they 45 are moved toward each other, they will fit firmly upon opposed faces of a rail R. Each of these strips have their upper portions movable into line with opposed faces of the standard 1 and for the purpose of holding the jaws in rail gripping positions there is provided a sleeve 3 which is slidable 50 on the standard and is adapted to move downwardly so as to embrace the upper end portions of the jaws and prevent them from swinging apart. In Figures 1 and 2 this sleeve has been shown in holding position.

55 While the jaws are in engagement with a rail the standard 1 is prevented from tilting laterally. For the purpose of assisting the jaws in holding the standard against swinging in the direction of the rail, short

feet 4 diverge downwardly from the lower end of the standard and are adapted to bear upon the rail as shown particularly in Figure 2. An opening 5 can be provided in the standard for the reception of a padlock indicated by broken lines at L for receiving any other suitable locking means whereby the sleeve 3 will be held against elevation off of the upper ends of the jaws. 60 65

The upper end of the standard has a laterally extending arm 6 provided with spaced collars 7 and mounted for rotation on this arm and between the collars is a sleeve 8 having a depending flag 9. The flag and sleeve can be formed of metal and the flag can be of any color desired. In the upper portion of the flag there may be provided an opening 10 for the reception of the bail of a lamp or for the reception of any suitable means looped about the sleeve 8 for the purpose of fastening the lamp to the arm. 70 75

The free end of the arm 6 projects laterally beyond the flag and has a yoke 11 pivotally connected at 12, one end of this yoke being movable into a slot 13 into the end of the arm. A transverse opening 14 is provided in the free end of the yoke for the reception of a padlock or the like so that the yoke can thus be held against upward 80 movement relative to the arm. A stop lug 15 is preferably carried by the yoke and is adapted to bear downwardly on the arm 6 so as to limit the downward swinging movement of the yoke. 85 90

Another yoke 16 is pivotally connected to one side of the standard 1 and is similar in construction to the yoke 11. This yoke 16 has its free end movable through a slot 17 in the standard and an opening 18 is extended transversely through the free end portion of the yoke for receiving a padlock or the like. A lug 19 is extended from the yoke adjacent this pivoted end and is designed to bear against the standard so as to limit the swinging movement of the yoke in one direction. 95 100

In using the device herein described the sleeve 3 is lifted so as to release the strips 2 constituting the rail gripping jaws. Said jaws are then opened outwardly as shown in Figure 3 and placed over a rail at the point where the signal is to be located. After the jaws have been swung toward each other to grip the rail the sleeve 3 is lowered and 105 can be fastened by means of a padlock L or the like. If it is desired to display a lamp 110

at the free end of the arm 6 the yoke 11 is 5 swung upwardly, the bail B of the lamp is placed on the arm and the yoke is swung downwardly over the bail and fastened. Instead of locating the lamp in this position it can be arranged on the standard 1, being suspended from the bail 6 as will be obvious. If preferred, however, the bail of the lamp 10 can be fastened to the center of the flag by inserting a fastening means through the opening 10 and around the sleeve 8. Obviously various other arrangements can be provided.

A signal device of this type is especially 15 useful beyond the ends of a car located on a siding and serve as a danger signal. It can also be used at points where track work is being done. In fact it will be found useful for any kind of work along railroads where 20 the positions of the signal devices must be changed frequently.

What is claimed is:

1. A signal device including a standard having an arm at one end, a flag suspended 25 from the arm, opposed rail engaging members pivotally connected at one end to the other end of the standard, and a member slidable on the standard for embracing the pivoted

members to hold them in gripping engagement with a rail.

2. A signal device including a standard having an arm at one end, a flag suspended from the arm, opposed rail engaging members pivotally connected to the other end of the standard, a slideable member on the standard 30 for embracing said members to hold them in engagement with the rail, a lamp retaining bail pivotally mounted, and means for limiting the movement of the bail in one direction.

3. A signal device including a standard, opposed rail engaging strips pivotally connected to the standard, a sleeve slideable on the standard for engaging the strips to hold them against movement, an arm extending 45 from the standard, lamp retaining bails pivotally connected to the arm and standard, each of said bails having a free end portion movable into the arm and standard respectively, each free end portion having a 50 fastener receiving opening, and means on the bail for limiting the swinging movement thereof in one direction.

In testimony that I claim the foregoing as my own, I have hereto affixed my signature.

HERBERT B. NICKELL.
